United States Patent Office

Des. 205,442
Patented August 9, 1966

205,442

SPONGE MOP

Raymond C. Tillinghast, Memphis, Tenn., assignor to
Gem, Incorporated, Byhalia, Miss., a corporation of
Mississippi

Filed Apr. 26, 1965, Ser. No. 84,951

Term of patent 14 years

(Cl. D9—2)

Fig-3

Fig-4

Fig-5

FIGURE 1 is a perspective view of a sponge mop, showing my new design.

FIGURE 2 is a bottom perspective view.

FIGURE 3 is a side elevational view thereof.

FIGURE 4 is a front elevational view.

FIGURE 5 is a top perspective view of a modified form of the design shown in FIGS. 1-4.

FIGURE 6 is another modified form of the design shown in FIGS. 1-4.

The dominant features of my design resides in the portions shown in full lines, the fragmentary showing of the handle being for illustrative purposes only.

I claim:

The ornamental design for a sponge mop, as shown and described.
